[57] CLAIM

The ornamental design for a wall panel or similar article, as shown and described.

DESCRIPTION

FIG. 1 is a front elevational view of a wall panel or similar article showing my new design;

FIG. 2 is a side elevational view thereof, the opposite side elevational view being identical thereto;

FIG. 3 is a rear elevational view thereof;

FIG. 4 is a top plan view thereof, the bottom plan view being substantially identical thereto;

FIG. 5 is a sectional view of a portion thereof showing the relief features of the panel, taken along the plane indicated by lines 5—5 of FIG. 1.

FIG. 1

FIG. 2

FIG. 3

FIG. 5

FIG. 4
